COMBINED HOLDING AND COUPLING DEVICE

Filed Nov. 7, 1923

J. N. Sheller,^{Inventor}

By Geo. P. Kimmel
Attorney

UNITED STATES PATENT OFFICE.

JOHN N. SHELLER, OF DANVILLE, ILLINOIS.

COMBINED HOLDING AND COUPLING DEVICE.

Application filed November 7, 1923. Serial No. 673,304.

To all whom it may concern:

Be it known that I, JOHN N. SHELLER, a citizen of the United States, residing at Danville, in the county of Vermilion and 5 State of Illinois, have invented certain new and useful Improvements in Combined Holding and Coupling Devices, of which the following is a specification.

This invention relates to a combined holding and coupling device, designed primarily for use in connection with a pair of trousers for coupling a belt and a suspender strap therewith, but it is to be understood that a device, in accordance with this invention can 10 be employed for any purposes for which it is found applicable, and the invention has for its object to provide, in a manner as hereinafter set forth, a device of such class with means for detachably connecting there- 15 with a belt and suspender tab or section, as well as further securely and detachably coupling, at the desired position to the waist portion of a pair of trousers, the belt or suspender tab or section.

20 Further objects of the invention are to provide, in a manner as hereinafter set forth, a device for the purpose referred to, which is simple in its construction, strong, durable, detachable, thoroughly efficient in 25 its use, conveniently applied with respect to the waist portion of a pair of trousers, and inexpensive to manufacture.

With the foregoing and other objects in 30 view, the invention consists of the novel construction, combination and arrangement of parts as hereinafter more specifically described and illustrated in the accompanying drawings, wherein is shown an embodiment of the invention, but it is to be understood 35 that changes, variations and modifications can be resorted to which come within the scope of the claims hereunto appended.

In the drawings wherein like reference characters denote corresponding parts 40 throughout the several views:—

Figure 1 is a fragmentary view, in front elevation, of a part of the waist portion of a pair of trousers, showing the adaptation therewith of a combined holding and coupling device in accordance with this invention and with a portion of the belt and a suspender tab connected to the device.

Figure 2 is a view similar to Figure 1,

with the part of the waist portion of the trousers shown in rear elevation and further 55 showing the device connected to the waist portion and having a suspender tab coupled therewith.

Figure 3 is a section on line 3—3, Figure 1, showing the adaptation thereof in connection with a belt, a suspender tab and the 60 waist portion of a pair of trousers.

Figure 4 is a grouped perspective view illustrating the elements of the device.

Referring to the drawings in detail, 1 denotes the waist portion of a pair of trousers, 2 a suspender tab which is positioned at the rear of the waist portion 1, and 9 a belt which is arranged against the outer face of the waist portion 1. The tab 2 and belt 9 70 are connected together by a combined holding and coupling device in accordance with this invention, and are further coupled to the waist portion 1 by said device.

A combined holding and coupling device, 75 in accordance with this invention, comprises a belt holding or supporting section and a suspender tab connecting section and with the said sections having cooperating means for detachably connecting them together and further with the supporting section having means for connecting it to the waist portion 80 of a pair of trousers and with the cooperating means for detachably connecting the sections together further providing for the 85 coupling of the sections to the waist portion of the trousers.

The supporting section consists of a substantially elongated vertically disposed integral rectangular frame formed of a front 90 bar or member 4, a bottom bar or member 5, a top bar or member 6 and a rear bar or member 7. The members referred to are formed integral with each other and the members 4 and 7 are of materially greater 95 length than the width or length of the members 5 and 6. The vertically disposed frame forms an opening 8 for the passage of a belt 9, and said frame not only constitutes means for supporting the belt 9 but further for 100 maintaining the belt in position at the front of the waist portion 1 of the trousers. The opening 8 formed by the frame, is of greater length than the width of the belt 9, so that the latter can conveniently slide through 105 the frame when occasion requires.

Projecting rearwardly from the member 7 is a pair of spaced holding bars 10, 11, which when the holding section is mounted in position with respect to the waist portion 1 of the trousers pierces the material from which the waist portion is made, in a manner as shown in Figure 3, whereby the holding section is retained in the position to which it has been set, or in other words the 10 bars 10 and 11 prevent the shifting of the holding section on the waist portion 1.

Projecting rearwardly from the member 7, and arranged between the bars 10 and 11, is a pointed shank 12, formed with peripheral threads 13. The shank 12 is of greater length than the length of the bars 10 and 11 and is inserted through the waist portion 1, as shown in Figure 3, and further projects inwardly from the inner face of 20 said waist portion 1.

The connecting section is circular in contour and consists of a disk 14, having formed integral with the rear face thereof, a tapered cylindrical extension 15, having its 25 greater diameter of the same diameter as the disk 14, and with the greater diameter of the extension 15 at the rear end of the extension.

The rear face of the extension 15 is formed 30 with a concavity 16. The connecting section has a centrally arranged opening 17 formed with a threaded wall and which engages with the threaded terminal portion of the shank whereby the holding section and connecting section are detachably connected together.

The tapered extension 15, in connection 40 with the disk 14, provides the connecting member with a peripheral groove 18 having a flat wall 19 and an outwardly inclined wall 20, which projects from the wall 19. The groove 18 is adapted to receive the lower end of the tab 2, which is slotted in a known manner, as at 21, to allow the tab to pass 45 over the rear end of the extension 15 and seat in the groove 18. The inclined wall 20 of the groove 18 retains the tab on the extension 15.

The threaded terminal portion 13 of the shank 12, in connection with the threaded wall of the opening 17, provides means for coupling the sections of the device to the waist portion 1, of the trousers, as shown in Figure 3.

It is thought that the advantages of a 55 combined holding and coupling device, in accordance with this invention, can be readily understood from the foregoing description taken in connection with the accompanying drawings, particularly in view of the convenient manner in which the device can be coupled with the waist portion of a pair of trousers for the purpose of connecting a belt and a suspender therewith, and although the preferred embodiment of

the invention is as illustrated and described, yet it is to be understood that changes in the details of construction can be had which will fall within the scope of the claims hereunto appended.

What I claim is:—

1. A combination holding and coupling device comprising an integral holding and an integral connection section, said holding section consisting of a vertically disposed rectangular frame formed of flat top, bottom, front and rear bars and providing a rectangular opening for the passage of a belt, said frame having its rear bar provided with a plurality of rigid piercing bars and a rearwardly extending threaded shank, and said connecting section consisting of a disk and a tapered extension having its reduced end projecting rearwardly from the disk thereby providing in connection with the disk a peripheral groove gradually increasing in width outwardly and providing means for the connecting of a suspender with the connecting section, said connection section having means cooperating with the threaded shank for detachably connecting the sections together and further for coupling the device in position.

2. A combined holding and supporting device comprising a belt holding section consisting of a polygonal-shaped integral frame providing an opening for the passage of a belt, the walls of said opening being uninterrupted from end to end, a rearwardly extending threaded shank integral with the outer face of the rear of said frame, and a suspender connecting section provided with means threadedly engaging with said shank for detachably connecting said sections together and further for coupling the device in position, said connecting section provided intermediate its ends with a peripheral groove for the reception of a suspender tab.

3. A combined holding and coupling device for the purpose set forth comprising a continuous holding section formed with a rectangular opening for the passage of a belt and further provided with a rearwardly extending integral threaded shank, and a peripherally grooved suspender connecting section threadedly engaging with said shank whereby the sections are connected together and detachably coupled in position, said holding section further provided with a plurality of rearwardly extending rigid holding bars.

4. A combined holding and supporting device comprising a holding section in the form of a polygonal-shaped frame providing an opening for the passage of a belt and a rearwardly extending threaded shank formed integral with the rear face of said frame, and a peripherally grooved suspender connecting section having an axial bore with the wall thereof threaded for

threaded engagement with said shank to connect said sections together and further for coupling the device in position upon a garment, said holding section further having formed integral with the rear face thereof a plurality of spaced rigid right angularly disposed piercing

In testimony whereof, I affix my signature hereto.

JOHN N. SHELLER.
